Patented Mar. 18, 1919.

UNITED STATES PATENT OFFICE.

FREDERICK H. EMERY, OF SCRANTON, PENNSYLVANIA.

RAILWAY-CROSSOVER.

1,297,812.

Specification of Letters Patent. Patented Mar. 18, 1919.

Application filed August 29, 1918. Serial No. 251,901.

To all whom it may concern:

Be it known that I, FREDERICK H. EMERY, citizen of the United States, residing at Scranton, in the county of Lackawanna and 5 State of Pennsylvania, have invented certain new and useful Improvements in Railway-Crossovers, of which the following is a specification.

My present invention has to do with rail- 10 way cross-overs.

It has for its general object to provide, in a railway cross-over, a bridge, flush at all points with the bottoms of the channels in the cross-over, and hence adapted to afford 15 a surface for the travel of wheel flanges during the passage of the wheels across the flange spaces between the proximate ends of the cross-over portions on which the treads of the wheels bear, this with a view to averting 20 the wheel treads dropping in the said spaces and giving rise to the objectionable pounding which is detrimental to the cross-over and the wheels and subjects car passengers to great discomfort. According to 25 my invention the upper side or surface of the bridge is at places in parallelism with the cross-over surfaces on which bear the treads of the wheels, with the result that incidental to the traverse of the cross-over 30 the wheels are supported by engagement with the wheel flanges and treads except when the mentioned spaces are encountered, when the wheels will be supported by engagement with their flanges, alone, though 35 the relative arrangement is such that the crossing of the flange spaces is negotiated without dropping or raising of the wheels and consequently without any bumping or excessive wear at the points adjacent to the 40 said spaces.

The invention also contemplates the provision of a bridge arranged to receive all of the wear at and adjacent to the space-crossing point, and adapted to be expeditiously removed and as readily replaced with a new bridge when occasion demands, thereby obviating the necessity of installing an entirely new cross-over which entails considerable expense and loss of time.

50 The invention further contemplates the adaptation of cross-overs such as are at present in use or in stock for use in conjunction with my novel and advantageous bridge. Manifestly, when deemed expedient, bolts

or other connecting devices may be employed 55 to secure my novel bridge in its stationary relation to the cross-over, without departure from the scope and principle of my claimed invention, though I would have it here understood that one feature of my present invention resides in the capacity of the 60 peculiar bridge by coöperation with the seat in the cross-over to retain itself in position without liability of casual movement or displacement.

With the foregoing in mind, the invention will be fully understood from the following description and claims when the same are read in connection with the accompanying drawings, hereby made a part hereof, in 70 which:

Figure 1 is a plan of the cross-over constituting the best practical embodiment of my invention that I have as yet devised.

Figs. 2 and 3 are vertical sections taken 75 through the body and bridge of the cross-over in the planes indicated by the lines 2—2 and 3—3, respectively, of Fig. 1—*i. e.*, at right angles to each other.

Fig. 4 is an edge elevation of the cross-over as it appears when the bridge is in operative position, and showing the flush relative arrangement of the bridge throughout.

Fig. 5 is a perspective of the bridge *per se*. 85 Similar numerals of reference designate corresponding parts in all the views of the drawings.

My novel cross-over body 1 is preferably 90 in one piece, as shown, with channels 2 formed in the upper side of the body and extending from edge to edge thereof and disposed at right angles to each other. The bottom walls 3 of the said channels 2 are parallel to the upper surfaces 4 of the cross-over body, which surfaces 4 may be properly denominated head surfaces inasmuch as in common with the rail heads they are adapted for the traverse of the treads of the car wheels.

Formed in the bottom walls 3 of the channels 2, at and beyond the point of intersection of the channels, is the cruciform seat 5 for the correspondingly shaped bridge 6 which may be and preferably is made of the 105 same material as the body 1. The bottom wall 7 of the seat 5 is parallel to the bottom walls 3 of the channels 2, and the end walls

of the seat are preferably, though not necessarily, perpendicular to the bottom wall 7 and rounded or concaved horizontally as illustrated. The bridge 6 is of a shape and size to snugly fit and occupy the seat 5 and is of such vertical thickness that its upper side rests flush with the bottom wall 3 of the channels. By virtue of this the bridge is enabled to retain itself in position and 10 against casual shifting or displacement without the employment of extraneous devices such as bolts, though it is to be understood that, without affecting my invention, such devices may be employed if regarded of 15 advantage.

Notwithstanding the capacity of the bridge 6 to hold itself against casual shifting or displacement, it will be noted that the bridge may be readily removed when 20 worn and replaced with a new bridge, thereby at comparatively small expense prolonging the usefulness of the cross-over as a whole.

In the practical use of my novel cross-over, the bridge 6 affords a supporting surface for the wheel flanges when the wheel treads encounter the flange spaces in the cross-over body, and hence there is no liability of the wheels dropping into the said 30 spaces and giving rise to the shocks and jars so often experienced in addition to subjecting the cross-over to undue strains and wear. There is little or no liability of the bridge 6 being grooved or otherwise worn by the 35 wheel flanges, but when such deterioration takes place the bridge, as before indicated, may be readily replaced with a new bridge at small expense and without interfering with traffic.

40 Having described my invention, what I

claim and desire to secure by Letters Patent, is:

1. In a railway cross-over, the combination with a cross-over body having intersecting channels at angles to each other, 45 with the bottom walls of the channels parallel to the upper sides of the tread portions and flange-spaces between said tread portions, and also having a cruciform seat in the bottom walls of the channels, the end 50 walls of said seat being perpendicular to the bottom wall thereof and concave horizontally; of a bridge, of cruciform configuration and size to snugly occupy the seat in the cross-over body, disposed in said seat, 55 with its upper side throughout flush with the bottom walls of the channels and parallel to the upper sides of the tread portions of the body.

2. In a railway cross-over, the combination with a cross-over body having intersecting channels at angles to each other, with the bottom walls of the channels parallel to the upper sides of the tread portions and flange-spaces between said tread portions, 60 and also having a cruciform seat in the bottom walls of the channels; of a bridge of cruciform configuration and size to snugly occupy the seat in the body, disposed in said seat, with its upper side throughout flush 65 with the bottom walls of the channels and parallel to the upper sides of the tread portions of the body.

In testimony whereof I affix my signature in presence of two witnesses.

FREDERICK H. EMERY.

Witnesses:

THOMAS R. HUGHES,
GEORGE F. SCHOLLA.
